(57) CLAIM

The ornamental design for mountain sports equipment, as shown and described.

DESCRIPTION

FIG. 1 is a first perspective view of mountain sports equipment in an open position according to the present invention. FIG. 2 is a first lateral view of a mountain sports equipment in an open position according to the present invention.

FIG. 3 is second lateral view of a mountain sports equipment in an open position according to the present invention. FIG. 4 is a front view of a mountain sports equipment in an open position according to the present invention.

FIG. 5 is a perspective back view of a mountain sports equipment in an open position according to the present invention. FIG. 6 is a top view of a mountain sports equipment in an open position according to the present invention.

FIG. 7 is a bottom view of a mountain sports equipment in an open position according to the present invention. FIG. 8 is a first perspective view of a second embodiment of mountain sports equipment in a closed position according to the present invention.

FIG. 9 is a first lateral view of a second embodiment of mountain sports equipment in a closed position according to the present invention. FIG. 10 is a second lateral view of a second embodiment of mountain sports equipment in a closed position according to the present invention. FIG. 11 is a front view of a second embodiment of mountain sports equipment in a closed position according to the present invention.

FIG. 12 is a back view of a second embodiment of mountain sports equipment in a closed position according to the present invention.

FIG. 13 is a top view of a second embodiment of mountain sports equipment in a closed position according to the present invention; and,

FIG. 14 is a bottom view of a second embodiment of mountain sports equipment in a closed position according to the present invention.
